EDWIN L. HENDERSON, OF WAUSAU, WISCONSIN, ASSIGNOR TO WILSON-HURD COMPANY, OF WAUSAU, WISCONSIN, A CORPORATION OF WISCONSIN.

FLY SWATTER.

Application filed July 8, 1927. Serial No. 204,241.

This invention relates to an improvement in fly swatters and has for its object to provide a device of this character which is of extremely simple and durable construction, reliable and effective in operation, and easy and comparatively inexpensive to manufacture.

One type of fly swatter which has been extensively used over a long period consists of 10 a wire handle provided at its outer end with arms to which a striking member, usually wire mesh, is secured by a sheet metal casing. The problem of fastening the sheet metal casing in such manner as to secure the same to 15 the striking member and to the handle and to maintain the assembly of these parts has been a more or less troublesome one and various expedients have been resorted to in an attempt to satisfactorily solve the problem. In some instances rivets, eyelets, or 20 similar fastening means have been employed to aid in the proper fastening of the sheet metal casing, striking member and handle in assembly, but the disadvantage of this 25 expedient resides in the fact that it adds another operation to the process of manufacture as well as another set of elements to the device, consequently increasing the expense. As devices of this kind find a wide use as 30 advertising specialties it is essential that their cost be kept down to the very minimum.

In an attempt to eliminate the rivets or other fastening means it has been proposed 35 to form the sheet metal casing with a plurality of over-lapping portions which are crimped or pressed into engagement with each other and into engagement with the striking member and handle. The solution 40 which the present invention provides for the problem is along this latter line but differs from anything that has been done heretofore in the material simplification of the manufacturing process and in the elimination of 45 any waste of the metal used to form the sheet metal casing. Along with these advantages the present invention provides a positive interlock between the assembled parts.

50 In carrying out the present invention a striking member is provided and may be of wire mesh with the exposed edges thereof, bound with tape or the like. The lower corners of the striking member are folded over 55 to provide pockets which receive diverging

arms formed at the upper end of the wire handle. A sheet metal casing covers the lower portion of the striking member and the diverging arms of the handle. This sheet metal casing is constructed of a single 60 piece of metal and is so shaped that two such sheet metal casings may be cut without waste from a rectangular or square blank. The sheet metal casing is folded transversely and has its folded portion crimped around one of 65 the arms and the portions of the striking member embracing such arm. One of the ends of the casing is extended around the other arm and laps over the other end of the casing, both of these ends being crimped into 70 permanent engagement with each other and into crimping engagement with the portions of the striking member and with the arm of the handle with which they are associated. The crimped casing provides positive stops 75 cooperable with the diverging arms of the handle to afford a positive interlock and this is had in a construction which is adapted to 80 simplified and comparatively inexpensive manufacturing process.

85 Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view in elevation showing a 90 fly swatter embodying the present invention;

Figure 2 is an enlarged fragmentary elevational view of the opposite side of the swatter from that shown in Figure 1;

Figure 3 is a view in transverse section on line 3—3 of Figure 2; and,

Figure 4 is a plan view showing how the sheet metal casing is struck from the blank.

Referring to the drawings it will be seen that in the present embodiment of the invention the fly swatter comprises a wire handle designated generally at 1 and having a looped or double gripping portion 2, a shank portion 3 wherein the strands of the wire handle are inter-twisted and diverging arms 4.

A striking member 5 is provided and is shown as comprising a suitably shaped piece of wire mesh which has its exposed edges 100 taped or bound as indicated at 6. The lower corners of the wire mesh striking member 5 110

are folded over as at 7 to define pockets which receive the diverging arms 4 of the handle.

A sheet metal casing designated generally 5 at 8 is provided and serves to cover the lower portion of the striking member, the folded corners 7 thereof and also the diverging arms 4 of the handle and to secure and maintain these parts in assembly. This sheet metal 10 casing 8 is constructed of a single piece of metal and is so shaped and folded as to be adapted to be struck from the blank with a minimum of waste, and yet the very construction that makes possible the practical 15 elimination of waste also simplifies the assembling operation and insures the security of the parts in proper position and relation with respect to each other during the life of the swatter. As shown in Figure 4, two 20 sheet metal casings 8 may be struck from a single rectangular blank. For the sake of clearness in illustration, Figure 4 shows one of the casings struck from the blank in full lines and the other in dotted lines. Each 25 sheet metal casing is of substantially triangular form although the corners of the blank are preferably cut away and each casing has an extension 9, which, in the blank, is an extension of a portion of the base of 30 the triangle. After being cut away from the blank the sheet metal casing 8 is folded transversely along its transverse median line *a*, the fold *a* providing a bight portion 10 from which side sections 11 and 12 of the 35 casing extend.

In the assembly, the bight portion 10 embraces one of the arms 4 of the handle and the portions of the striking member associated with such arm 4 and the two side sections 11 and 12 of the casing lie on the opposite sides of the lower portion of the flexible member. The end of the casing on which the extension 9 is formed is extended around the other arm of the handle and 40 around the portions of the striking member associated with such other arm and over-laps the end portion 11^a of the other end of the casing. After the sheet metal casing has been assembled in this manner with the striking member and the handle, it is crimped inwardly around the arms of the handle as indicated at 13, 14, 15 and 16 (see Fig. 3), these crimps providing positive stops or 45 shoulders coacting with the diverging arms 50 to prevent loosening or disassembly of the parts and acting to firmly and securely hold the striking member, handle and casing in

assembly. Thus, not only are the arms of the handle retained in the pockets formed by folding over the lower corners of the striking member but the casing itself is maintained in proper position. This advantage is had with a single piece of sheet metal casing which has a single set of over-lapping ends. In other words, at one side of the 55 swatter there is a closed bight 10 and at one side only is there the over-lapping of the ends. As shown in Figure 4, the central portion of the blank is cut out at *b* to provide the opening which accommodates the shank 70 of the handle.

In this way the swatter not only has a secure fastening of its parts and a generally durable construction without the use of rivets or other fastening devices but waste in the production of the sheet metal casing is minimized. The general durability of the swatter is greatly enhanced by forming the closed bight or gripping portion at one side of the swatter and having but a single set of 80 over-lapping ends at the other side of the 75 swatter.

The faces of the side sections of the single piece casing are adapted to receive advertising matter.

The invention claimed is:

1. A fly swatter comprising a handle having arms, a striking member having portions engaged with the arms and a single piece sheet metal casing covering the arms and the lower end of the striking member, said casing having an intermediate bight portion of closed formation which embraces and secures a portion of the striking member to one of said arms and having a single set of over-lapping ends for securing the striking member to the other arm.

2. A sheet metal casing for use in securing a striking member of a fly swatter to a handle and comprising a single piece of 100 metal of substantially triangular form adapted to be struck with a minimum of waste from a blank and having an extension from a portion of the base of the triangle, said casing being bent along the altitude of 105 the triangle to provide a bight-like gripping portion, the extension of the base portion of the triangle and the remaining portion of the base being shaped to provide a gripping arrangement.

In witness whereof, I hereunto affix my signature.

EDWIN L. HENDERSON.
